Primary Examiner — Shawn T Gingrich*Assistant Examiner* — Anehita E Oribabor(74) *Attorney, Agent, or Firm* — Lerner David LLP(57) **CLAIM**

The ornamental design for a cooling plate for battery, as shown and described.

DESCRIPTION

FIG. 1 is a front perspective view showing the overall configuration of a cooling plate for battery according to our new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a bottom perspective view thereof;

FIG. 9 is an enlarged view showing a portion 9 of FIG. 1;

FIG. 10 is an enlarged view showing a portion 10 of FIG. 1; and,

FIG. 11 is an enlarged view showing a portion 11 of FIG. 8. The dash-dot-dot lines illustrate boundaries of the enlarged partial views and form no part of the claimed design.
